UNITED STATES PATENT OFFICE.

GEORGE F. SHIELDS, OF KERN, CALIFORNIA.

CURLING-IRON.

No. 846,854.

Specification of Letters Patent.

Patented March 5, 1907.

Application filed August 19, 1905. Serial No. 274,879.

To all whom it may concern:

Be it known that I, GEORGE F. SHIELDS, a citizen of the United States, residing at Kern, in the county of Kern, State of California, have invented certain new and useful Improvements in Curling-Irons; and I do hereby declare the following to be a full, clear, and exact description of the invention, such as will enable others skilled in the art to which it appertains to make and use the same.

This invention relates to electric curling-irons, and has for its object to improve the construction shown in my prior patent, No. 15 784,438, dated March 7, 1905.

To this end the invention consists in the formation of a handle in two sections, each of which is provided with a registering bore and with a pair of recesses communicating therewith, whereby the binding-posts, supply-wires, and resistance-coil may be more readily and perfectly affixed in place than has heretofore been possible where a solid or one-piece handle has been in use.

25 The invention further consists in the construction, combination, and arrangement of parts, all as hereinafter fully described, specifically claimed, and illustrated in the accompanying drawings, it being understood that changes in form, proportion, size, and minor details may be made within the scope of the claims without departing from the spirit or sacrificing any of the advantages of the present invention.

35 In the drawings, Figure 1 is a side elevation of my invention. Fig. 2 is a longitudinal sectional view of my invention. Fig. 3 is a transverse sectional view.

Referring now more particularly to the accompanying drawings, the reference character 1 designates a handle having a longitudinal bore 2 therethrough, in which bore are formed the recesses 3 and 4, one recess being arranged in advance of the other. A tube 5, of glass, porcelain, or any other suitable material, has one of its ends in the aforesaid longitudinal bore 2 of the handle 1, with its opposite or outer end closed, as indicated by the reference character 6. This tube 5 is 45 filled with suitable insulating material 7; and embedded in this insulating material is a heating-coil 8, which by reason of the insulating material 7 is held from engagement with the inner surfaces of the tube 5. The 50 oppositely-disposed terminals 9 and 10 of the

heating-coil 8 pass through the open end of the tube 5 and are connected with short binding-posts 11 and 12, respectively, which binding-posts are disposed in the respective recesses 3 and 4 of the bore 2 of the handle 1. 60 Circuit-wires 13 and 14 are connected to the respective binding-posts 11 and 12 and lead outwardly through the open end of the handle 1 opposite the end in which the aforesaid tube 5 is inserted for connection with a suitable battery to direct the current into the heating-coil 8 for heating the tube 5. This tube 5 also serves as a clamping member.

The handle 1 is composed of two members 15 and 16, which are connected together at 70 one end through the instrumentality of a suitable fastener 17, which passes between the coils 18 of the circuit-wires 13 and 14, as shown in the drawings, the opposite ends of the members of the handle being clamped 75 together by means of a suitable ferrule 19, which latter is provided with a pair of ears 20, in which is pivotally mounted, by means of a suitable pivot-pin 21, a clamping member 22, provided with an integral handle 23, 80 there being a bent flat spring having its leaf 24 disposed against the under face of the handle 23 immediately in the rear of the said pivot-pin 21, with its opposite leaf 25 secured to the handle 1 by means of a suitable fastener 26 immediately in the rear of the ferrule 19. By reason of the bent flat spring just alluded to the handle 23 is held out of engagement with the handle 1 and the clamping member 22 in engagement with the 90 tube or clamping member 5.

Owing to the section formation of the handle, as has been described, and to the formation of the several recesses, the binding-posts may be affixed in the member 15 and connected with the terminals of the supply and heating wires before the opposite section 16 is positioned and secured by the ferrule and bolt, thus positively insuring a perfect connection of the several wires and at the same 95 time providing for a quicker and more exact and effective arrangement of the several parts, while in no way increasing the cost of manufacture.

From the foregoing it will be understood 100 that pressure upon the handles 1 and 23 will separate the clamping members 5 and 22, so that the hair may be pinched therebetween for curling. It will be apparent also that the directing of current into the heating-coil 8

will heat the tube or clamping member 5 to the desired capacity, and it is to be understood that this heating-coil may be of any suitable resistance.

5 What is claimed is—

An electric curling-iron comprising a handle formed of a pair of sections each of which is provided with a longitudinal bore and with a pair of recesses intermediate the ends of said bore and communicating therewith, the recesses and bores registering when the sections are secured together; binding-posts arranged in the recesses of one member and extending into the recesses in the opposite member; a tubular clamping member; a heating-coil in said clamping member, the terminals of the heating-coil being connected with

the binding-posts; circuit-wires connecting the binding-posts and leading outwardly of the bore of the handle; a ferrule embracing the sections of the handle, said ferrule having spaced ears; a second clamping member pivotally mounted in the ears of said ferrule and provided with a handle; and a spring arranged between the handles to hold the 25 clamping members in engagement with each other.

In testimony whereof I affix my signature in presence of two witnesses.

GEORGE F. SHIELDS.
